WOODEN PARQUET FLOORING BLOCK AND METHOD AND APPARATUS FOR PRODUCING THE SAME

Charles E. Tibbals, Oneida, Tenn., assignor to Wood Products Development Company, Inc., Oneida, Tenn., a corporation of Tennessee

Filed Jan. 29, 1958, Ser. No. 711,868

12 Claims. (Cl. 144—318)

The present invention relates to an improved method and apparatus for the production of parquet flooring blocks and to an improved block formed thereby.

This application is a continuation-in-part of my earlier filed co-pending United States applications Serial No. 657,184, filed May 6, 1957; Serial No. 666,322, filed June 18, 1957 (now Patent No. 2,961,021); and Serial No. 670,184, filed July 5, 1957.

The first of the applications (Serial No. 657,184) discloses the broad concept of cutting wooden strips into separate slats, the colation of a group of such slats into a block-forming assembly, and the securing of the slats of the group into a discrete flooring block through the medium of an adhesive web.

The second application (Serial No. 666,322, now Patent No. 2,961,021) proposes the retention of the block slats by a plurality of knurled wires embedded in the under surfaces of the slats. The specific method and apparatus involved a sawing of grooves in the slats, the insertion of the wire in the aligned grooves of the slat group forming a block, and the severance of the wire within the confines of a terminal slat of the block. To insure the proper positional relation of the wire and a succeeding block, the wire (after severance and initial insertion into sequentially advanced slat assemblies) is tensioned and pulled rearwardly relative to the direction of movement of the blocks prior to its final seated engagement in the second or succeeding block.

The most recent of these applications (Serial No. 670,184) was directed to the wire-retained block, per se, and to an assembly of such blocks made by the method and apparatus of my Patent No. 2,961,021.

The present invention now provides an improved, wire-retained parquet flooring block made by an improved method and an improved apparatus.

So far as the product is concerned, definite improvements over those disclosed and claimed in my earlier applications have been obtained. Notably, the depth of the groove in which the wire is seated has been appreciably reduced, thereby increasing both effective wear thickness and strength of the block. Additionally, the terminal ends of the wires are deformed and clinched into the terminal slats of the block, thereby increasing the block strength longitudinally of the wire. Further, the retention wires are of a softer, annealed, ductile type, thereby avoiding the inherent curvature of the final block caused by the former use of high tensile steel wire.

The improved method herein proposed avoids a rearward movement of the knurled and roughened wire in the slat grooves, thereby avoiding the inherent broaching of the grooves and the resultant enlargement thereof. The method further proposes the severing of the wire in positively timed sequence within the confines of both the forward and rearward terminal slats of each block and the subsequent removal of those wire remnants interposed between the finished blocks.

The apparatus of this invention is substantially more simple than that heretofore disclosed and specifically

2

eliminates the difficulty controlled fluid pressure operated wire kinking mechanism. A mechanically timed and cam-operated wire removal device driven from the common machine drive is utilized to remove the severed wire fragments bridging adjacent assembled blocks.

It is, therefore, an important object of the present invention to provide an improved wire-retained parquet flooring block formed of a plurality of individual slats and a retaining wire clinched into terminal slats of the block.

Another important object of this invention is the provision of an improved method of making a parquet flooring block from a plurality of individual wooden slats by inserting a continuous wire into grooves formed in the under side of the slats, sequentially severing the wire within the confines of successive blocks, gripping the wire remnants intermediate the blocks, and removing the wire remnants.

A further important object of this invention is the provision of an improved apparatus for making parquet flooring blocks and including sequentially operable wire cutting and removing devices which are driven from a common machine drive.

Yet another object is to provide an improved parquet flooring block wherein a plurality of slats are retained by a common wire which is positioned within slots formed in an under surface of the slats, the retention wire being relatively soft, annealed, ductile steel and being deformed at its extremities toward the interior of the block to, in effect, form an elongated staple.

Still another object is the provision of an improved method of forming parquet flooring blocks by the assembly of wooden slats into a block unit, severing the retaining wire within the confines of the block unit, and simultaneously deforming the wire cut end into the interior of each terminal block slat.

It is a still further object of this invention to provide an apparatus wherein a rotatable cutter sequentially contacts each of a pair of block units to sever a retaining wire, and a wire remnant removal device is interposed between the successive block units to remove a severed wire remnant therefrom.

Other objects and advantages of the invention will appear from the following detailed description taken in conjunction with the annexed drawings.

As shown on the drawings:

General method

In Figure 1, the entire method and apparatus of the present invention is diagrammatically illustrated.

As shown in Figure 1, elongated, relatively narrow wooden strips of a width and thickness suitable for the formation of rough finished parquet flooring blocks are formed into cut slats of desired size by passing the strips through a gang cutter, preferably of the rotary saw type wherein a plurality of uniformly spaced saw blades are disposed upon a common power driven shaft. The strips are of random length, thus permitting the use of otherwise unusable scrap material.

The cut slats are then conveyed longitudinally from the slat conveyor to a sorting station at which the slats are sub-divided into unassembled block units containing the appropriate number of slats necessary to form a complete flooring block. These unassembled units are formed by a transversely operating, reciprocating sorting mechanism. The block units are conveyed laterally for transfer onto an endless drive chain provided with means for separating, and retaining the identity of, the individual block units. Actually, a pair of endless chains are preferably utilized. These chains and other apparatus elements herein disclosed are duplicated as (for example, two securing wires are utilized), but the description of one such element will suffice for both.

The cutting apparatus, the slat conveying apparatus, and the sorting mechanism are fully described in my earlier filed application Serial No. 657,184, hereinbefore referred to. This cutting, conveying and sorting mechanism forms no part of the present invention and need not be disclosed in detail herein.

After having been transferred to the drive chain, the slats are conveyed in unassembled, but unit separated, groups to an assembly drum about which the drive chain is partially lapped. Prior to introduction of the chain onto the assembly drum, the under surfaces of the slats are grooved by contact with one or more circular saws which cut partially through each slat. As the drive chain is partially lapped about the assembly drum, the slat units are deformed to a concave configuration and, while being retained in this configuration, a wire is guided into each of the grooves formed on the under surface of the slats.

The general concept of the drive chain, the assembly drum, and the use of saws to groove the under surface of the slats is disclosed in my above-identified Patent No. 2,961,021. This mechanism forms no part of the

present invention and need not be disclosed in detail herein.

The wire which is utilized for retaining the slats in block form is preferably passed from a supply coil 5 through a wire knurler to the vicinity of the assembly drum. At the drum, the wire passes beneath a pivotal holding dog for retaining the wire under tension. The feeding of wire is controlled by a pivotal wire tension arm contacting the wire intermediate the knurler and 10 the holding dogs. As illustrated in Figure 1, increased tension in the wire, as will occur when the wire is in short supply, will elevate the wire tension arm and trip a limit switch which controls operation of the wire knurler to supply wire. When sufficient wire has been 15 supplied to form the nominal slack in the wire reach, the limit switch will be deactivated and the wire knurler will cease operation or more slowly operate.

Of this wire supply mechanism, the holding dogs and the general use of a knurling machine is to be found 20 in my Patent No. 2,961,021, issued November 22, 1960. However the utilization of the wire tension arm and the limit switch to control operation of the wire knurler is novel as disclosed in this application.

The wire is inserted into the aligned slat grooves under 25 tension and the wire is severed by a wire cutter of a novel type which is hereinafter more fully described and claimed. This wire cutter actually employs a pair of cutting knives which are spaced peripherally of the assembly drum to sequentially sever the wire adjacent the trailing edge of one block unit and adjacent the leading edge of the next successive block unit. The two successive blocks thus are joined by a short length or "remnant" of wire.

Following passage of the wire cutter, the assembled 30 blocks are interposed between the assembly drum and an insert roller which firmly seats the wire within the block groove. Next, the short wire remnant intermediate successive blocks is removed by a wire remnant remover driven by the drive chain and actuated in timed 35 sequence to the travel of the blocks to grasp the wire remnant and to remove the same from the finished block. The finished, discrete, assembled flooring unit is removed 40 from the drive chain by a block removal conveyor lapped about a drive chain return roller. Following removal of 45 the block, the drive chain is returned to pick up additional block units.

From the foregoing general description, it will be appreciated that the present invention thus provides certain 50 improvements in a continuous method of making parquet flooring units.

General assembly

The general apparatus of the present invention utilizes a pair of transversely spaced link-type conveyor chains 55 to convey pre-assembled flooring block units through the assembly process.

As illustrated in Figures 2 and 24, each such chain comprises spaced chain blocks indicated generally at 30, and interconnected by longitudinally spaced chain links 31. The chain blocks 30 lie outside the longitudinal extremities of the individual slats 32 (Figures 2 and 8) and the intermediate links 31 of each of the chains overlie the lateral longitudinal outer extremities of the slats 32. This relationship of the chain blocks 30, chain links 31, and slats 32 is best illustrated in Figure 20 of the drawings.

The chains are guided by idler sprockets, such as 70 sprocket 33, and the chain is driven by the terminal or removal sprocket 34, by suitable means as disclosed in my first filed pending application Serial No. 657,184. The chain passes about a head sprocket 35 which is positioned closely adjacent an assembly drum, indicated generally at 36. This assembly drum 36 is substantially the same as that disclosed in my earlier applications and 75 comprises a central shaft 37 (journalled upon a support

frame 38), a plurality of radial spokes 39, and a central peripheral slat-contacting peripheral surface 40. The lateral extremities of this surface 40 are defined by a pair of radially enlarged ribs 41 (Figures 2 and 18). The transversely spaced chains correspond in spacing to the transverse spacing of the ribs 41, the chain blocks 30 fitting snugly against the inner directed faces of the ribs 41, so that the slats 32 will be laterally confined therebetween. It will be noted that the links 31 lie outside the confines of the blocks 30, with the inner links 31 of each chain overlying the adjacent longitudinal extremity of each slat 32. The chain links 31 thus confine the slats 32 against the peripheral surface 40 of the assembly drum. Inasmuch as the chain is maintained under tension, it assumes a concave configuration corresponding to the convex curvature of the peripheral surface 40 of the drum 36.

From Figures 24 and 18, it will be seen that spaced chain blocks 30 are provided with transversely projecting lugs 42 which extend inwardly to project beyond the links 31. These lugs 42 serve to separate the groups of slats defining the preassembled block units as supplied to the chains.

As best illustrated in Figure 1, it will be seen that the pre-assembled slats are placed upon the chain in longitudinally spaced relation. The spacing between adjacent slat pre-assemblies correspond to the longitudinal dimension of the lugs 42 and the spacing between the lugs corresponds to the longitudinal extent of each group of slats.

The lugs 42 perform one other function, and that is to urge the drum-contacting edges of the slats 32 into snug lateral abutment, as explained in my earlier filed applications.

Preceding the assembly of the slats, and preferably prior to the confining of the slats against the peripheral surface 40 of the drum 36, transversely spaced grooves are formed in the under surface of the slats. These grooves are indicated by reference numeral 45 in Figures 21, 22 and 23, the grooves being generally rectangular in cross-section and opening onto the under surface of each of the slats. These grooves are formed by the operation of circular saws indicated generally at 46 in Figure 2 of the drawings. Such saws having been disclosed in my Patent No. 2,961,021, issued November 22, 1960, and need not be described in detail in this application.

Thus, by the time the slats are brought into contact with the convex surface 40 of the drum 36, the slats have been grooved and the grooves of adjacent slats will necessarily be aligned, inasmuch as the slats were pre-assembled into block unit prior to the grooving operation.

Next, a wire is placed in each of the spaced grooves 45. The mechanism for placing a wire in each of the grooves is illustrated in Figures 1, 2, 18 and 19 of the drawings. Generally, the wire may be described as a low carbon, low tensile, annealed but not quenched, number 6 carbon wire. This wire is ductile and soft, but has sufficient tensile strength to withstand its feeding into the slat grooves and to maintain the slats into an assembled block.

The wire knurler, indicated generally at 50 in Figure 1, affords an excellent means for controlling the feeding of wire to the block assembly apparatus. This wire knurler 50 is of the conventional type and includes a plurality of wire knurling rolls 51 operative upon the exterior surface of the wire to deform it into conventional knurled form. Two such knurlers are provided, one for each side of the block to feed a wire strand 52 from a wire supply 53.

The strand 52 is led beneath a wire tension arm 55 pivoted, as at 56, to a fixed point (such as the wire knurler housing) and having at its free end a terminal roller 57 contacting the wire strand 52. Changes in the tension of the wire 52 will necessarily change the

relative vertical position of the wire tension arm 55. Changes in position of the wire tension arm are utilized to actuate and de-actuate a limit switch 58. This limit switch may turn the wire knurler off and/or may vary the speed of operation of the wire knurler to maintain a substantially constant tension in the wire strand 52 and a substantially constant feeding rate therein. Thus, the combination of the limit switch 58 and the wire tension arm 57 provides means for controlling the feeding of the wire, and also means for synchronizing the operation of the two separate wire knurlers 50 (one such knurler, limit switch, and wire tension arm being provided for each wire strand).

Each wire strand 52 is held against the block slats 32 by a holding dog assembly indicated generally at 60 in Figures 18 and 19. A substantially identical holding dog assembly has been earlier described in my Patent No. 2,961,021, issued November 22, 1960, and need be only generally described here.

Generally, the holding dog assembly 60 comprises a generally inverted U-shaped frame defined by transverse element 61 and vertical elements 62 secured by suitable means to a pair of arcuate supporting bars or angle irons 63 generally underlying the assembly drum 36 for supporting various assembly elements, as will be herein-after more fully described. The holding dogs per se each comprise dog tooth elements 65 rigidly connected to a depending actuating arm 66, the rigid tooth and arm assembly being disposed for rotation about pivot pins 67 carried by the transverse frame member 61. Two such dog tooth and arm assemblies 65, 66 are provided in transversely spaced position, the teeth being aligned with the slots or grooves 45 formed in the slats 32 (Figure 18).

The dog teeth 67 are urged into contact with the exposed under surfaces of the slats 32 by coil compression springs 68 interposed between the arms 66 and a transverse spring reaction plate 69 carried by the frame elements 63. Thus, it will be seen that the wire strands 52 are trained beneath and urged against the slats by the dog teeth 65. The dog teeth thus serve initially to urge the wire strands 52 into the slot grooves 45 and primarily to prevent any rearward movement of the strand 52 because of the tension therein.

Following the positioning of the wire strands 52 against the under surface of the blocks and partially within the grooves of the slats, the block slats and wire strands are subjected to the successive action of a wire cutter, a wire insert roll, and a wire remnant remover heretofore generally described and hereinafter particularly described. The final finished block 70 (Figure 1 and Figures 20-23, inclusive) is then removed from the wires by operation of a block removal conveyor operating between the wires in the manner set forth in my Patent No. 2,961,021, issued November 22, 1960.

Wire cutting apparatus

The wire cutting apparatus of the present invention is particularly illustrated in Figures 3-7, inclusive, hereof.

This wire cutting apparatus includes a transverse drive shaft 71 journaled for rotation in bearings 72 supported on bearing blocks 73 from the arcuate support angles 63. This transverse shaft has secured thereto for rotation therewith, as by heat or the like (not shown), a pair of transversely spaced drive sprockets 74. These drive sprockets 74 mesh with the chains 30 as the chains are lapped about the assembly drum. Thus, rotation of the assembly drum and longitudinal displacement of the chain drives the shaft 71.

Also mounted on the shaft 71 axially adjacent each of the sprockets 72 is a wire cutting assembly denoted generally by reference numeral 75. These cutter assemblies 75 may satisfactorily comprise a central, generally cylindrical body portion 76 and an outer retainer plate 77. Preferably, co-rotation of the sprockets 74 and the cutter

assemblies 75 is insured by the use of cap screws or the like 78 having enlarged heads 79 contacting the end plates 77 of the cutter assembly and threadedly retained by aligned apertures 74a in the sprocket 74. Co-rotation of the shaft 71 and the sprocket-cutter assembly 74, 75 may be insured by a key 75a.

The cutter assembly 75 carries four individual cutters 80. These cutters have body portions 81 which are rectangular in cross-section and which are recessed into the body portion 76 of the cutter assembly 75, as in radial slots 82 (Figure 7). The cutters 80 are retained in radially adjusted position by set screws 83, inserted in threaded apertures 84 in cover plate 77. Additionally, the cutters 80 are retained against radial displacement by the cover plate 77.

It will be noted from Figure 6 that the body portion 76 of the cutter assembly 75 is of larger diameter than either the associated sprocket 74 or the associated cover plate 77. The outer peripheral edge 85 of the body portion 76 is of reduced width, the width of the portion 85 being determined by a pair of beveled outer peripheral portions 86 of the body portion, and the peripheral extremity 85 being of a width less than that of the slot 45 of a superimposed slat 32. The radial dimension of the periphery 85 of each cutter assembly 75 is such that it will project into the groove 45 and tend to urge the wire strand 52 upwardly in the slot 45. This peripheral surface 85 is recessed, as at 87, to accommodate the cutter elements 80 and also to accommodate the passage of a chain lug 42 between the cutters 80.

The timed relationship between rotation of the cutter assemblies 75 and an adjacent group of slats is best illustrated in Figures 4 and 5, wherein it will be seen that the two adjacent cutters 80 span two different groups of slats 32 and the chain lug 42 interposed therebetween. The leading cutter 80 of each pair of cutters projects into the terminal slat 32 of one group of slats to sever the wire strand 52, and the trailing cutter 80 of each pair of cutters projects into the leading terminal slat 32 of the next succeeding group of slats to sever the wire. The cutters 80 thus sever the wire strand 32 in two places bridging adjacent groups of slats to form a wire "remnant" 90 bridging the groups of slats and a length of wire 91 of a longitudinal extent less than that of the group of slats.

Further, as best shown in Figure 5, the severance of the wire necessarily deforms the end 92 of the length of wire 91 upwardly relative to the cutter shaft 71, radially inwardly relative to the assembly drum 36 and toward the upper surface of the terminal slat 32 of the group of slats. The terminal cutting edge of each of the cutters 80 is of a transverse extent greater than the width of the slot or groove 45 formed in each of the slats 32.

Thus, it will be seen that operation of the cutter assembly 75 severs the wire strand 52 into discrete, predetermined lengths 91 sufficient to secure the slats of each group of slats into a final block 79 and also to deform the wire ends 92 upwardly into the body of the terminal slats 32. Due to the provision of two pairs of cutters 80 for each cutter assembly 75, the wire is severed at four places during each revolution of the cutter assembly shaft 71. The remnants 90 are of a length greater than the lugs 42 so as to bridge the gap between adjacent groups of slats 32, this length being determined by the peripheral spacing of the cutters 80 of each pair of cutters. The extent of deformation of the wire 91 into the superimposed terminal slat 32 is determined by the radial extension of each cutter 80 beyond the radial dimension necessary to merely sever the wire. Obviously, the location of the severed end 92 of the wire 91 within the terminal slat 32 is determined by the peripheral positioning of the cutters 80, while the extent of deformation may be varied by varying the radial adjustment of the cutters 80.

Wire insert rolls

Following the severing of the wire strand 52 into the discrete wire lengths 91 binding the slats of each group into a final block assembly, and the wire remnants 90, 5 the knurled wire is driven home in the grooves 45 by insert rolls illustrated in Figures 8-11, inclusive.

These wire insert rolls are denoted by reference numeral 100 and are carried by transversely extending shafts 101 similar to the cutter assembly shaft 71 heretofore described. The insert rolls 100 are secured by suitable means, as by bolts 102, to sprockets 103 for co-rotation, and the roll-sprocket assembly 103 is maintained in co-rotatable relation with the shaft 101 by suitable means, as by key 104.

15 The insert roller 100 is provided with a radially beveled side surface which tapers to a substantially reduced peripheral wall 105, which wall is of a transverse size smaller than the corresponding dimension of the groove 45 in the slats 32. The term "insert roller" describes the function of the rollers 100 inasmuch as the reduced peripheral surface 105 thereof enters the groove 45 and firmly pushes the wire upwardly into the slat groove to bottom the same therein.

Wire remnant remover

The means for removing the short wire remnant interposed between successive block assemblies and severed by the wire cutting apparatus heretofore described is illustrated in Figures 12-17, inclusive.

20 Generally, this wire removal device comprises a transverse shaft 110 journaled in fixed bearings 111 which are carried by the side walls 63 heretofore described to underlie the assembly drum 36. Underlying the shaft 110 and 25 in alignment with a radius common to the shaft 110 and the shaft 37 of the drum 36 is a lower support plate 112.

Disposed upon the shaft 110 and secured thereto for co-rotation therewith are a pair of transversely spaced sprockets 113. These sprockets 113 are substantially 30 identical with sprockets 103 and 74 heretofore described. Upon rotation of the drum 36 and upon longitudinal advancement of the chains 30, the shaft 110 will be rotated in timed relation.

Disposed upon the shaft and extending generally radially therefrom are two pairs of diametrically opposed 35 wire-engaging devices 115. All four of these devices 115 are identical and the description of one will suffice for all four.

As best illustrated in Figures 14 and 15, each pair 40 of removal devices 115 is secured to the shaft by means of a pair of diametrically extending bolts 116 extending through shaft apertures 117. Confined by the heads of the bolts 116 on one side and by nuts 118 on the other side of the shaft are a pair of retainer plates 120 best illustrated in Figure 17. These plates each include a diagonally extending slot 121 intermediate plate apertures 122 which are adapted to receive the bolts 116. A rectangular recess 123 is provided adjacent one lateral extremity of the plate 120. The slot 121 and the recess 55 60 65 70 75 123 cooperate to define therebetween a generally triangular embossment 124 and a second trapezoidal embossment 125.

As shown in Figure 12, the plates 120 serve to retain 80 upon the shaft the wire removal elements 115, which comprise a first or stationary gripping element 130 and a second or movable gripping element 131 movable relative to the fixed element 130 about a pivot pin 132. The fixed gripping element 130 has an extension 133 adapted to be retained within the slot 121, and the movable element 131 has a depending extension 134 movable within the rectangular recess 123. To aid in retaining the gripping elements 115 upon the shaft 110, the shaft is provided with a peripheral recess 135 and the plate 120 and the bolts 116 cooperate to maintain the fixed gripping element extension 133 in fixed position in the shaft recess 135. The

movable extension 134 of the movable element 131 is movable within the recess 123 and shaft recess 135.

The gripping elements 131 and 130 are moved relative to one another by cam means including a cam follower or roller 140 journalled upon a depending, angularly related extension rod 141 secured to the free end of the movable extension 134, as by a cylindrical block 142 welded to the rod 141 and to the extension 134.

The cam follower 140 cooperates with an adjustable arcuate cam 145 which is carried from the fixed plate 112 by an upstanding cam arm 146. The cam follower 140 is confined against the arcuate cam 145 by an upstanding roller guide 147 also carried by the plate 112. To maintain the gripping elements 130 and 131 in a normally spaced, non-gripping relation, a tension coil spring 150 is utilized to interconnect the cam rods 141 of that pair of elements 115 aligned axially of the shaft 110. It will be noted from Figure 2 that this spring, because of its tensile strength, normally pulls the cam followers 140 toward the vertical center line of the shaft 110, thereby moving the movable element extension 134 in a counter-clockwise direction. Contact between a cam roller 140 and the arcuate cam 145 will urge the movable element extension 134 in a clockwise direction. These directions of movement apply only to the left hand pair of radially aligned elements 115, and these directions are reversed for the right hand pair of gripping elements 115.

The operation of the gripping device, as illustrated in Figures 12-17, inclusive, will be readily understood inasmuch as the operation of the fixed element 130 and the movable element 131 of each pair is identical with the operation of a pair of pliers.

The timing of the operation is controlled by engagement of the sprocket 113 with the chain 30 so that rotation of the shaft 110 is so synchronized with rotation of the drum as to bring a gripping element 115 intermediate each block or block group of slats. The location of the cam 145 is such that a cam roller 140 is in contact with the cam surface whenever the corresponding gripping unit 115 is inserted between adjacent block units. Thus, the elements 130 and 131 are positioned so that their extremities lie on either side of the wire remnant as the lug separating a pair of adjacent block units approaches alignment with a common radius of the shaft 110 and the shaft 37 of the drum 36.

Next, the movable element 131 is forced toward the fixed element 130 by engagement of the cam follower 140 with the cam surface 145. As the follower 140 moves over the face of cam 145, the movable element 131 is moved into engagement with the wire remnant 90, and the remnant is clamped between the elements 130 and 131 as illustrated in Figure 16 of the drawings.

Further advancement of the drum will displace the slat groups to the left, as indicated by the directional arrow of Figure 13, and continued rotation of the shaft 110 will likewise rotate the gripping device 115 to the left, the peripheries of the path of movement of the gripping element and the drum diverging rapidly, because of the differences in diameters of the sprocket 113 and of the drum 36. It will be noted that the face of the cam 145 has an appreciable dwell period during which time the gripping elements 130 and 131 remain in gripping engagement with the wire remnant 90, this extended period of time being sufficient to bodily lift the wire remnant from its position intermediate the adjacent groups of slats. The gripping means 115 is opened by movement of the movable element 131 thereof away from the fixed element 130 thereof. Such opening movement is accomplished through the medium of the tension spring 150. Of course, opening movement of the gripping elements 115 will release the wire remnant from its gripped position, and the wire remnant will fall free of the gripping means and of the finished block.

The blocks now are finished after having removed the wire remnants, and the blocks are separated from one

another so as to be in their final individual and discrete form.

Finished product

5 The product of the present invention is illustrated in Figures 20-23, inclusive. The finished block comprises a plurality of individual slats 32 which are retained in a close, but non-abutting relation by the ductile wire 91. The spacing between the adjacent slats is effected by virtue of the concave shape onto which the block is forced by its confirmation to the assembly drum 36 and the insertion of the wire strand 52 into the grooves 45 of the block undersurface while the block is concave.

10 The generally rectangular grooves 45 are slightly undersize with respect to the wire 91, so that knurled wire is firmly seated within the slat grooves. Further, as will be particularly evident from Figure 22, the forcing of the free end 92 of the wire 91 into the body of the terminal slat 32 aids materially in preventing longitudinal displacement of the slats from the completed block 70. It has been found that the clinched wire 91 functions almost as an elongated staple in retaining the slats against displacement. The improved longitudinal strength of the finished block 70 is due in large 15 measure to the clinching of the terminal wire portions 92.

20 As illustrated in Figure 23, the severance of the wire by the operation of the cutting elements 80 also forms a depression or dimple 92a extending transversely of the slot or groove 45. The occurrence of this dimple has 25 been found not to be deleterious to the quality of a complete block assembly.

25 The utilization of ductile, low carbon, annealed wire has been found to be extremely desirable, inasmuch as such wire has very low inherent resiliency, the blocks readily return to a flat condition after they have been removed from the forming drum, and the easily severed wire clinches easily and abruptly, as at 92, into the terminal slats.

30 Of course, the blocks 70 possess all of the advantages hereinbefore described in my earlier filed application Serial No. 670,184 since all the block edges may readily be beveled and/or finished without interference of the wire with the finishing tools or processes.

35 While preferred embodiments have been described above in detail, it will be understood that numerous modifications might be resorted to without departing from the scope of the invention as defined in the following claims.

40 What is claimed is:

1. In a method of making a parquet flooring block by the assembly of a plurality of individual elongated slats of rectangular cross-section and each having a groove therein, the steps of inserting a wire into the grooves of the group of slats, severing the wire within the confines of each terminal slat only of said group of slats, and deflecting the wire end only into the non-grooved portion of the terminal slat, thereby imbedding the wire end in the body of said slat.

45 2. In an apparatus for forming a parquet flooring block by the assembly of a plurality of individual identical wooden slats having aligned grooves therein while said slats are conveyed in an arcuate path, means for guiding a continuous wire strand into the slat grooves, cutting means for severing the wire adjacent the leading and trailing edges of the block as said slats travel in said path, wire gripping means located adjacent to but outside the path of travel of said slats for engagement with an exposed portion of the severed wire projecting

50 into the groove but partially lying outside of the confines of the slats, and means for moving said gripping means in an arcuate path diverging from that of said slats in the direction of slat movement.

55 3. In an apparatus for continuously forming successive groups of grooved slats into discrete flooring blocks,

the slats being carried by spaced conveyor chains having lugs separating the slat groups and the chains being deflected into an arcuate path, means for guiding a continuous wire strand into the slat grooves, cutting means sequentially severing the strand at spaced locations at the leading and trailing edges of each group of slats, and means for engaging and removing the wire remnants intermediate said groups and including a pair of relatively movable gripping elements, rotary means carrying said elements for rotational co-movement, cam means for relatively moving said elements into and out of gripping relation with said wire remnants at predetermined rotative positions thereof, and means engageable with said chain for driving said rotary means.

4. In a method of making a parquet flooring block by the assembly of a plurality of individual elongated slats of rectangular cross-section, the steps of transversely grooving each slat, guiding a wire into the grooves of a group of slats, seating said wire in said grooves, severing the wire within the confines of each terminal slat of said group of slats and during said severing deforming each severed end only of the wires into the body of the terminal slats beyond the confines of said grooves.

5. In a method of making parquet flooring blocks by the assembly of successive block groups each comprising a plurality of individual elongated slats having transverse grooves therein, the steps of inserting a continuous wire into the grooves of successive groups of slats, seating said wire in said grooves, sequentially severing the wire at spaced points located within the confines of each terminal slat of said group of slats, and simultaneously deforming the end wire into the terminal slats, positively gripping the severed wire remnants intermediate adjacent groups of slats, removing the gripped remnants from contact with the adjacent groups of slats, and then releasing the gripped remnants.

6. In a method of making a parquet flooring block by the assembly of a plurality of individual elongated wooden slats of rectangular cross-section, each of said slats having a groove formed therein adjacent the longitudinal terminal edges thereof, the steps of inserting into each of said grooves an elongated wire of a length greater than the composite transverse dimension of the slats, sequentially severing the wire within the confines of each terminal slat of said group, and simultaneously deforming the ends only of the severed wires into the terminal slats.

7. In an apparatus for continuously forming successive groups of grooved slats into discrete flooring blocks, the slats being carried in spaced groups by conveyor means, means for guiding a continuous wire strand into the slat grooves as the slats are supported and carried by said conveyor means, cutting means sequentially severing the strand and having peripherally adjacent cutting elements sequentially severing the wire at the trailing edge of a leading group of slats and at the leading edge of a trailing group of slats, actuatable gripping means for subsequently engaging and removing the wire remnants intermediate said groups and means for actuating said gripping means.

8. In an apparatus for forming a parquet flooring block by the assembly of a plurality of individual identical wooden slats having aligned grooves therein, means for conveying said slats in a path, means for guiding a continuous wire strand into the slat grooves, rotary cutting means for severing the wire in said grooves as said slats travel in said path, wire gripping means located adjacent the path of travel of said slats for gripping an exposed portion of the severed wire lying outside of the confines of the slats and having another portion lying in said groove, and means carrying said gripping means

for movement in a path diverging from that of said slats to remove the gripped wire portions from said groove.

9. In a method of making parquet flooring blocks by the assembly of successive block groups each comprising a plurality of individual elongated slats of rectangular cross-section, the steps of sequentially advancing spaced block groups, grooving each slat, guiding a continuous wire strand into the grooves of successive groups of slats, a portion of the wire strand bridging the interval between successive block groups, seating said wire in said grooves, successively severing the wire within the confines of the trailing terminal slats of one such group and within the confines of the leading terminal slat of the next successive group, gripping the severed remnant of said strand intermediate said groups, removing the gripped remnant from engagement with said terminal slats, and then releasing the gripped remnant.

10. In a method of making a parquet flooring block by the assembly of successive block groups each comprising individual elongated wooden slats of rectangular cross-section having aligned grooves formed therein adjacent the longitudinal edges thereof, the steps of conveying said groups in spaced succession in an arcuate path, inserting into the grooves of successive groups an elongated wire strand, sequentially severing the wire strand within the confines of each terminal slat of said group, gripping the severed wire segments intermediate said groups, and conveying said gripped and severed segments in a divergent path to remove the same from the slat grooves.

11. In an apparatus for continuously forming successive groups of grooved slats into discrete flooring blocks, the slats being carried by spaced conveyor chains having lugs separating the slat groups and the chains being deflected into an arcuate path, the improvements of means for guiding a continuous wire strand into the slat grooves, rotary cutting means having peripherally spaced cutting elements sequentially severing the strand at spaced locations at the leading and trailing edges of each group of slats, means for engaging the severed wire remnants intermediate said groups, means for moving the engaging means relative to said groups of slats to remove the severed remnants from said slat grooves, and means for releasing said engaging means after removal of said remnants.

12. In a method of making a parquet flooring block by the assembly of a group of individual elongated slats of rectangular cross-section, each of said slats having a groove formed therein adjacent the longitudinal terminal edges thereof, the steps of inserting into each of said grooves an elongated wire and deforming the respective ends only of said wires into the body of the terminal slats only of said group of slats short of the outside edges of said terminal slats.
